UNITED STATES PATENT OFFICE.

ARTHUR B. LAMB, OF WASHINGTON, DISTRICT OF COLUMBIA.

ANTIDIMMER FOR RESPIRATORS AND THE LIKE.

1,418,264.

Specification of Letters Patent. Patented May 30, 1922.

Application filed June 17, 1920. Serial No. 389,690.

To all whom it may concern:

Be it known that I, ARTHUR B. LAMB, a citizen of the United States, and residing in Washington, District of Columbia, have 5 invented certain new and useful Improvements in Antidimmers for Respirators and the like, of which the following is a specification.

This invention relates to respirators or 10 gas masks of the type wherein both the purified and exhaled air are allowed to flow through the interior of the face-piece of the mask coming in contact with the lenses and also the type wherein a mouth-piece is employed for inhaling and exhaling air. In 15 respirators as previously made, the moisture laden air upon being exhaled would strike the lenses which are usually at such a temperature as to cause the temperature of the 20 warm, moist air to fall below its dew point and deposit water, thus obscuring the vision. Many attempts have been made to remedy 25 this defect by various expedients such as drawing the air to be breathed over the lenses and by the use of anti-dimming compositions which gave only temporary relief. Gelatine or cellulose acetate lenses hitherto used are also unsatisfactory in that they 30 soften and become distorted under service conditions.

Among the objects of this invention is the production of a respirator which shall not be subject to dimming of the lenses and in order to accomplish this I provide a device 35 which forms the eye-piece and includes an arrangement of members which precipitate out a large part of the moisture from the exhaled air or air which has derived its moisture from other sources such as from 40 the face and eyes before it reaches the lenses, thus preventing the deposition of appreciable amounts of water on the same. A respirator so constructed is of further advantage in that the eye-piece needs no attention from the wearer, and there are no 45 spare parts to be carried, bulky wiping folds in the face-piece are made unnecessary, the vision is clear at all times, and the eye-piece is held always in the proper position in 50 front of the eyes.

I provide an eye-piece utilizing the conductivity of different materials as the underlying principle. A cooling or radiating member is attached to the respirator in such 55 a manner that the exhaled or humid air comes in contact with a portion of the same

before reaching the lens. The dew point of the air is raised by the condensation of water vapor upon the cooling member so that little or no moisture condenses upon the 60 lens. To further prevent dimming the lenses may be heated by a specially constructed device which has the additional function of holding the respirator in its adjusted position. This invention also 65 contemplates the use of a double lens with an air or gas filled space between and may also include a disk of thin gelatine or surface hydrolyzed cellulose acetate for the inner lens to cut down the effects of condensation 70 if any. When hydrolyzed cellulose acetate is used, the condensed water is absorbed by the hygroscopic material and made to run out into a film. Each of the above improvements is considered a distinct advance in the 75 construction of respirators and various combinations of my improvements are preferably made to adapt the invention to various working conditions.

In the accompanying drawings which 80 illustrate a preferred embodiment of the invention, Fig. 1 represents an exterior view of the improved respirator in adjusted position on the wearer. Fig. 2 is a horizontal cross-section of the eye-piece some parts being shown in elevation. Fig. 3 is a vertical section along line 3-3 of Fig. 2. Fig. 4 shows an interior view of an improved eye-piece, some parts being broken away to more clearly illustrate the manner in which the 90 parts are assembled, and Fig. 5 shows the eye-piece separate from certain of its accessories.

The face-piece 1 of the respirator which is of ordinary construction is held to the 95 head of the wearer by flexible bands 2 and has inlet and exhaust passages 3 and 4, respectively, of any well known construction. The specially constructed eye-piece is formed of a radiator 5 which is preferably 100 a thin metallic sheet, as of aluminum, having openings 9 formed therein to correspond with the ordinary eye-piece. The radiator 5 is joined to a cylindrical member 6 which is placed in the opening 9 and extends inwardly and at its innermost portion is covered by a disk 7 which carries a grid or condenser 8, all these parts being preferably of aluminum. This grid also serves as a protection to the eye of the wearer, especially 105 in case the lens becomes broken. A set of lenses 10 comprising preferably inner and

outer lenses 11 and 12 are fitted into an insulating ring 13 made preferably of hard rubber. The ring fits tightly into the metallic cylinder 6 but prevents contact between the cylinder and the lenses. The inner lens is bound by a metallic ring 14 which in turn is connected to upper and lower metallic bars 15 and 16, respectively, which are connected with face pieces 17 and 18, respectively, the upper one of which is adapted to rest upon the forehead of the wearer and the lower upon the cheek. The bars 15 and 16 pass through openings 19 in the cylinder 6 and are held spaced from the cylinder by 15 the insulating ring 13.

The embodiment shown in Fig. 5 differs but slightly from the form above described and comprises the radiator 5, the cylinder 6 and ring 7 carrying the grid 8. A set of 20 lenses 10 is placed as above indicated in position within the cylinder 6, the bars and accompanying face-pieces being omitted. If desired a ring carrying a disk of surface hydrolyzed cellulose acetate may be placed 25 upon the lenses of either form of eye-piece.

In use the action of the device is as follows:

The respirator is adjusted on the face and exhaled air flows in the direction of the 30 lenses. The outer air which is usually colder than the exhaled air cools the radiator 5 which conducts away heat from the grid 8 cooling it so that when the warm moist exhaled air strikes the grid a large portion of 35 its contained moisture is condensed and flows down. For additional protection against a deposition of water on the inner lens 11, the two lenses 11 and 12 are separated by an air-space which decreases the 40 cooling effect of the outer air. The inner lens is further heated by the heat of the body conducted by means of the face-pieces 17 and 18 through the connecting bars to the encircling ring 14. By the twofold action, 45 first, the cooling of the moist air and, second, the heating effect of the lens practically no deposition of water on the lens can take place under even the most unfavorable field conditions. This device is especially adapted 50 for use in cold or humid climates. The grid 8 but slightly cuts down the vision. In the embodiment of Fig. 5 only the cooling effect of the outer air is utilized, such an arrangement being in many cases sufficient.

55 It is to be understood that the heat for raising the temperature of the eye-piece lens need not necessarily come from the face but may be derived from some other source; furthermore, the introduction of heat to the 60 eye-piece lens is not limited to the use of the circular metallic ring 14, in fact in some instances it may prove desirable to place metallic strips across the eye-piece to facilitate the transfer of heat to the same.

65 The principles set forth herein are not

limited to eye-pieces or eye-pieces of respirators. In fact these principles may be adapted, by suitable means, to keeping moisture away from other surfaces, e. g., glass windows, goggles, etc.

70 Although I have described a specific form of eye-piece, I do not intend to limit myself to this embodiment of my invention but what I claim is broadly the idea of utilizing the heat conductivity of different materials as above described except as limited by the following claims:

What I claim is:

1. Means for preventing condensation of 80 water on substances having one surface exposed to warmer atmosphere than the opposite surface comprising a cooling element serving as a condenser in close proximity to and coextensive with the surface exposed to the warmer atmosphere.

85 2. Means for preventing condensation of water on substances having one surface exposed to warmer atmosphere than the opposite surface comprising a cooling element serving as a condenser in close proximity to the surface exposed to the warmer atmosphere and a radiator having a relatively large area exposed to the colder atmosphere and directly connected to said condenser.

90 3. Means for preventing condensation of water on windows and other glass objects having one side exposed to a warmer and more humid atmosphere than the opposite side comprising a metallic radiator of relatively large area exposed to the colder atmosphere and directly connected to a condenser in close proximity to the glass surface exposed to the warmer atmosphere.

95 4. An eye-piece for respirators comprising a radiator on the exterior of the respirator directly connected to a condenser disposed to assume a position between the lens of the eye-piece and face of the wearer.

100 5. An eye-piece for respirators comprising a metallic radiator of relatively large area on the exterior of the respirator directly connected to a vertical, metallic grid disposed to assume a position between the lens of eye-piece and face of the wearer.

105 6. An eye-piece comprising a cylinder of conducting material forming a lens space, a radiator having a relatively large area exposed to the outside atmosphere connected to said cylinder and to a metallic grid serving as a condenser.

110 7. Means for preventing condensation of water on a lens disposed in an eye-piece comprising a heating element adapted to be connected to the eye-piece.

115 8. In combination with an eye-piece, means for preventing condensation of water on a lens disposed in said eye-piece comprising a heating element connected to said eye-piece.

120 9. An eye-piece for respirators comprising a lens, a conducting member connected 125

thereto and means for conducting heat from the face of the wearer to the lens through said conducting member.

10. An eye-piece for respirators comprising a lens, a metallic ring encircling same and means for conducting heat from the face of the wearer to the lens through said metallic ring comprising a heating element having a conducting bar and a face-piece.

10 11. An eye-piece for respirators including a lens held by a metallic ring, conducting bars leading from the upper and lower ends of said ring and face-pieces connected to same adapted to contact with the forehead 15 and cheek, respectively, of the wearer.

12. Means for preventing condensation of moisture on windows, lenses and the like, comprising a condenser for taking up moisture from the air before reaching the glass 20 surface, said condenser being connected to a radiator for cooling same and a heating element connected directly to the glass object.

13. In a respirator, means for preventing condensation of water on lens of eye-piece comprising cooling and heating elements connected to said eye-piece and insulated 25 from each other.

14. An eye-piece for respirators comprising a cylinder of conducting material, a non-conducting ring within the same carrying the lens and insulating the lens from the cylinder, said cylinder and lens being connected with cooling and heating elements, 30 respectively.

15. An eye-piece for respirators comprising a metallic cylinder and insulating ring set into the same, a lens set in said ring, metallic face-pieces connected to said lens 35 through bars and encircling ring, a metallic grid placed between the lens and the face of the wearer and directly connected to the cylinder, a radiator connected to the exterior of the face-piece, the heating and cooling

elements being substantially completely insulated from each other. 45

16. In combination, a lens set comprising a holding, insulating ring in which is set a plurality of lenses separated by an air space and means for removing by condensation 50 moisture from air before reaching the surface of the lens exposed to humid atmosphere.

17. A lens set comprising a holding, insulating ring in which is set a plurality of 55 lenses separated by an air space, one of said lenses being surfaced with a material integral therewith for preventing same from becoming dimmed.

18. A lens set comprising a holding, insulating ring in which is set a plurality of lenses separated by an air space, one of said lenses being surfaced with hydrolyzed cellulose acetate integral therewith for preventing 60 same from becoming dimmed. 65

19. In an eye-piece, a lens surfaced with a material for preventing same from becoming dimmed and means for removing by condensation the moisture from air before reaching said lens. 70

20. In an eye-piece, a lens surfaced with a material for preventing same from becoming dimmed, means for removing by condensation the moisture from the air before reaching said lens and means for heating 75 said lens.

21. In an eye-piece, a lens surfaced with hydrolyzed cellulose acetate for preventing same from becoming dimmed and means for removing by condensation the moisture from 80 air before reaching said lens.

22. In an eye-piece, a lens surfaced with hydrolyzed cellulose acetate for preventing same from becoming dimmed, means for removing by condensation the moisture from 85 air before reaching said lens and means for heating said lens.

ARTHUR B. LAMB.
